UNITED STATES PATENT OFFICE.

ALLAN A. ADAMSON, OF BROOKLYN, NEW YORK, AND WILLIAM F. GRUPE, OF HUDSON HEIGHTS, NEW JERSEY.

PAPER-BOX MACHINE.

Application filed February 27, 1919. Serial No. 279,486.

To all whom it may concern:

Be it known that we, ALLAN A. ADAMSON and WILLIAM F. GRUPE, citizens of the United States of America, residing at Brooklyn, county of Kings, State of New York, and Hudson Heights, county of Bergen, State of New Jersey, have invented certain new and useful Improvements in Paper-Box Machines, of which the following is a specification.

This invention relates to machines for producing strips, and particularly strips having the finish paper applied to, adapted for rims for the cover and tray, and necks for a necked paper box.

The machine specifically set forth in this application forms a unit of the general necked box making machine, described and claimed in respect to features of the units, 20 in our copending application, identified as follows:—Scoring machines, Serial No. 278,418, filed February 21, 1919.

In such copending application the present machine or unit is referred to as the "strip 25 producer."

The present invention, as well as the above referred to separate units, respectively set forth in the aforesaid copending application, embodies the principle or process set 30 forth in our copending application entitled Method of making boxes, patented June 14, 1921, No. 1,381,097, comprising as a main object, the production of boxes by substantially concurrently forming the respective parts 35 of the box, including forming of the strips for the tray rim, neck and cover rim respectively, and the application of adhesive under substantially the same temperature and atmospheric conditions, and also substantially 40 without delay at the proper stage of production effecting the positioning of the cover on the tray.

The preferred form of box produced by our machine is finished with finish paper for 45 facing the exposed faces of the box, and means are provided for substantially concurrently supplying three indefinite lengths of paper board for the tray rim, neck and cover rim, respectively, means for concurrently supplying finish paper cooperating with the paper board supplying means, substantially concurrently applying the finish paper to the respective indefinite lengths of

paper board substantially concurrently cutting off the respective indefinite lengths to 55 the required lengths to form the respective strips for the tray rim, neck and the cover rim.

Such indefinite lengths of paper board are preferably previously treated, as set forth in 60 our copending applications Method of producing rim boards, Serial No. 240,463, filed June 17, 1918; Rim board, Serial No. 240,426, filed June 17, 1918; Rim board, Serial No. 240,425, filed June 17, 1918, now Patent 65 1,379,622, May 31, 1921, or scored as set forth in our aforesaid copending application Serial No. 278,418.

In the most preferred form of the present invention, as embodied in the specific form 70 set forth more particularly hereinafter, the present invention comprises separate means for respectively mounting three reels of paper board, separate means for mounting three reels of finish paper corresponding to 75 the paper board, means for applying adhesive to a face of each finish paper, preferably to effect a "strip" of adhesive of less width than the width of the face of the finish paper, means for respectively applying a 80 portion of the respective finish papers to the strips of paper board, means for respectively folding over the lateral extensions of such partially applied strips of finish paper onto the opposite faces of the respective strips of 85 paper board, means for subjecting to pressure the opposite faces of the respective strips of paper board having the finish paper applied thereon, means for feeding the required lengths of the respective strips of 90 paper board corresponding to the tray rim, neck and the cover rim, means for severing the said respective strips to the required lengths of the tray rim, neck and cover rim, and means for advancing the respectively 95 severed strips forwardly to the succeeding unit, or otherwise out of the strip producer.

Other features and objects of our invention will be more fully understood from the following description and the accompanying 100 drawings, in which—

Fig. 1 shows a side elevation of one form of our invention, certain parts being omitted for the sake of clearness;

Fig. 2 is a top plan view of Fig. 1, 105 omitting the reels of paper board;

Fig. 3 is a sectional view on line 3—3 of Fig. 1, showing the mounting means of the reels of finish paper;

Fig. 4 is a sectional elevation on line 4—4 of Fig. 1, showing the severing means arranged to cut butt joints for the tray rim, neck and cover rim, and the general actuating parts;

Fig. 5 is a detail sectional view on line 5—5 of Fig. 2, showing the finish paper applied to the respective strips of paper board and the lateral extensions of the finish paper turned upwardly at an angle;

Fig. 6 is a detail sectional view on line 6—6 of Fig. 2, showing the means for applying pressure to the strips of paper board, respectively having the finish paper applied on the under face of the strip of paper board;

Fig. 7 is a detail sectional view on line 7—7 of Fig. 2, showing the lateral extensions of the finish paper folded over onto the upper faces of the respective strips of paper board and also applied thereto;

Fig. 8 is a detail sectional view on line 8—8 of Fig. 2, showing the means of feeding the required lengths of the respective indefinite lengths of strips of paper board having the finish paper applied thereto;

Fig. 9 is a diagrammatic side elevation showing the operations of the aforesaid parts;

Fig. 10 is a diagrammatic perspective view, on a somewhat enlarged scale, indicating the concurrent treatment of the respective strips of paper board and the respective strips of finish paper, corresponding to the tray rim, neck and cover rim;

Fig. 11 is a detail bottom plan view, showing the preferred method of applying adhesive to the finish paper;

Fig. 12 is a detail sectional view on line 12—12 of Fig. 1, showing on a somewhat enlarged scale, of the finish paper and the adhesive applying means;

Fig. 13 is an oblique projection as viewed in the direction of the arrow 13 of the parts shown in Fig. 14, showing the skiving knives for the tray rim and cover rim and the actuating mechanism;

Fig. 14 is a side elevation of Fig. 2, with the front frame removed, showing the conjoint assembly of the butt and skive severing means, and also the clamping post of the tray rim, neck and cover rim in vertical section;

Fig. 15 shows in vertical elevation a modified form of continuous feeding and severing means;

Fig. 16 is a detail view showing the pin and slot connection between the collar 49 and the hub of lever 45, the parts being shown in spaced relation; and Fig. 17 is a detail;

As set forth, the particular embodiment

shown in the drawings comprises three similar sets of mechanism for respectively treating the three strips of paper board and the three strips of finish paper, corresponding to the tray rim, neck and cover rim respectively, and accordingly the detail description of the set of mechanisms corresponding to the tray rim will suffice to also describe the construction and operation of the sets of mechanism corresponding to the neck and cover rim, excepting for certain features referred to more particularly hereinafter.

However, it will be understood that many of the features of construction and method of treatment, comprised in our invention, so are applicable to machines for separately producing a strip, whether for the tray rim, or neck or cover rim. The particular embodiment of the invention shown in the drawings comprises substantially separate means for mounting a reel of paper board, separate means for mounting the finish paper, means for respectively supplying the paper board and finish paper and applying adhesive thereto, means for applying the finish paper to the paper board, for forming the tray rim, neck and cover rim, respectively, similarly arranged folding and clamping means for the three respective sets of mechanism, means for positively advancing the respective lengths of paper board having the finish paper applied thereto and means for severing such lengths from the indefinite lengths of the respective reels of paper board and finish paper, such parts being operated substantially simultaneously, whereby the paper board and finish paper are treated, and the adhesive applied thereto, under substantially the same temperature and humidity conditions.

The reel of paper board 1, see Fig. 1, is mounted on a collar 2, loosely mounted on the shaft 3, said collar 2 being fixed to the lateral, oppositely disposed spiders 4, for side-guiding the reel of paper board 1. The brake shoe 5 engages the collar 6, integral with the core 2, said shoe 5 being mounted on the arm 7 of the bell crank 8, pivoted at 9 on the bracket 10. The arm 11 of the bell crank 8 is tensioned by the coiled spring 12, adjusted in tension by means of the threaded rod 13 and the nut 14.

The opposite brackets 10 are supported on the rods 15, held by set screws in the hubs 16 in the upper extensions of the rear frame 17 and front frame 18. The frames 17, 18 are provided with the feet 19 and are suitably held together by the tie rods 20.

The reel of finish paper 21 is mounted and controlled by parts of similar construction and arrangement and like parts are designated by like reference characters. The rearward end 22 of paper board is threaded around the guide 23, provided with opposite lateral guide flanges 24, said guide

23 being supported on the shaft 25 passing from the front frame 18 to the rear frame 17.

The unwound end 26 of the finish paper is passed under the bar 27, of the adhesive fountain 28, thence over the adhesive roll 29, thence under the bar 30, similar to the bar 27. Each bar 27, 30 is provided with the opposite side guiding collars 31, 32. The 10 effective width of the roll 29 is preferably less than the width of the finish paper 26 and the sets of guide collars 31, 32 are arranged to effect the application of a "strip" 33 of adhesive, see Figs. 12 and 11, on the 15 strip 26 of finish paper, whereby the outer edges of the adhesive are at substantial distances from the edges of the finish paper 26. Such arrangement precludes the squeegeeing of any excessive adhesive beyond the 20 edges of the finish paper, when the strip of finish paper is applied to the paper board.

The portion of the finish paper having the adhesive applied thereto is shown at 34, which portion is threaded over the shaft 35, 25 and between the opposite collars 36. The paper board 22, after passing the guide 23 passes on the top of the finish paper 34, supported, as aforesaid, by the shaft 35.

Both the finish paper 34, and the paper 30 board 22, on the top thereof, pass over the top of the shaft 37 and between the opposite collars 38, 39 and under the spring 40, attached to the collar 41, mounted on the shaft 42. The collar 39 is beveled to turn 35 the lateral extension 41^a of the finish paper 34 up at an angle while the spring 40 applies pressure to the paper board and holds the paper board in proper position relative to the finish paper.

40 Progressing further, the paper board 22 and finish paper 34 are then subjected to further pressure by the idler rollers 42, 43. The lower roller 43 is supported on the shaft 44, and the upper roller 42 is supported on the lever 45, see Figs. 2 and 6, 45 loosely mounted on the shaft 46 and spring-pressed by the spring 47, adjustable by means of the collar 48, fixed to the shaft 46.

The collar 49 is provided with a pin 50 50 adapted to be received in the slot 51, disposed in the lever 45, said slot 51 being of greater width than the diameter of the pin 50, to allow play of the pin 50 within the slot 51, to attain freedom of movement of 55 the lever 45, under accommodating action of the spring 47.

The collars 49 are mounted on the common shaft 46, having the lever 52 fixed at the front end thereof, said lever 52 being provided with the plunger 53, pressed by the 60 spring 54, seated in the hub 55, having the knurled head 56. The plunger 53, upon downward manual movement of the lever 52, is adapted to be seated in the lower locating 65 recess 57, in which position, the springs 47

become effective in tensioning the idler rollers 42 on the upper faces of the strips of paper board, as indicated at 59, Fig. 1. Upon raising the lever 52 to seat the plunger 53 into the upper locating recess 58, the 70 pins 50 engage the respective ends of the slots 51 of the levers 45, respectively, and cause the levers 45 and therewith the idler rollers 42 to be raised, for the purpose of 75 convenience of threading and cleaning.

The paper board having the finish paper folded thereon and applied on both sides, indicated by 59, passes under the shoes 60, see Fig. 1 and Fig. 7, which are each replaceably held by a thumb screw 61, which is seated in the body portion 62 of the shoe. The posts 63, under action of the springs 64, exert pressure on the finish paper and paper board 59, which pressure is regulated by the nuts 65. The eccentric shaft 66 with 80 its throw-off lever 67 serves as a common means to throw all three shoes 60 out of operation. The paper board and finish paper 59 are subjected to further pressure by the 85 idler rolls 68 and 69 (see Fig. 1). The idler 90 rollers 68 and 69 are mounted and operated similarly to the idler rollers 42 and 43.

The paper board and finish paper 59 is fed forward between the side guides 70, see 95 Fig. 8, and the upper guide 71 by the clamping means comprising the upper member 72 and the lower member 73. The upper member 72 is a toe and is provided with the stud 75, and is resiliently held on the lever 74 by a split washer and nut. The lever 74 is 100 loosely pivoted on the shaft 76. The screw 77 and spring 78, with its adjustment nuts 79 adjust the pressure of the lever 74, and therewith the toe 72. The lever 80 is fixed to the shaft 76, and the opposite ends of the 105 shaft 76 are pivoted in the carriage 81. The lever 80 is provided with the lug 82, cooperating with the lug 83 on the carriage 81, whereby upon working of the lever 80, described more fully hereinafter, its lug 82 110 engages the lug 83, causes the carriage 81 to slide forwardly of the machine, to feed the desired length of the paper board and finish paper 59. The lever 80 is further provided with the stud 84, on which is pivotally mounted the link 85. The stud 86 is adjustably held on the lever 87 by means of a slot and clamping nut, to provide for adjustment of the extent of feed. Usually 115 the neck is of somewhat less length than the tray rim, or the cover rim, and such adjustment provides for the proper length of feed of the respective parts.

The lever 88 is fixed to the general rock shaft 89, said lever 88 being provided with 120 a slot to receive the stud 90, located in the slot by means of a nut. The link 91 is mounted at one end on the stud 90 and at its other end on the stud 92, fixed on the lever 93, fixed on the power shaft 94., 130

Upon rotation of the power shaft 94, the lever 88 and therewith the shaft 89 and the respective lever 87, see Figs. 1 and 8 are oscillated forwardly, causing the upper clamping member or toe 72 to oscillate downwardly in which movement the levers 80, 74 operate as a bell-crank until the toe 72 engages the paper board and finish paper 59, whereafter the spring 78 becomes compressed to an adjusted tension, until the lugs 82 and 83 are brought into engagement, whereby upon further forward oscillation of the levers 88, 87, the carriage 81 is caused to slide forwardly on the slides 95, 96. The slides 95 and 96 are supported on the bars 97, 98, which latter serve also to tie the frames 17 and 18 together. The extent of forward movement of the clamping member 72 is indicated in Fig. 10 and also in Fig. 1, by full and dotted lines, showing respectively the initial and final positions. The carriage 81, and therewith the lower clamping member 73, move forwardly to the same extent as the toe 72, the paper board and finish paper 59 being clamped and positively held between the clamping members 72, 73, during such forward or feeding movement.

It will be noted that the arrangement provided for, as just described, attains self-accommodation of the clamping members 72, 73, to different thicknesses of paper board or finish paper, or both, and at the same time insures the clamping of the paper board and finish paper 59 between the toe 72 and the lower clamping member 73 at a predetermined instant prior to any movement of the carriage 81. Upon the attainment of the carriage 81 to its final position forwardly, as indicated by dotted lines in Figs. 1, 9 and 10, the paper board and finish paper 59 is clamped in such forward position and held by the clamping bar 99, prior to severing of the paper board and finish paper by the severing means 100. The clamping bar 99 extends across all the strips of paper board and finish paper 59, for the cover rim, neck and tray rim, respectively, and is mounted at its opposite ends on the posts 101, and provided with the compression springs 102, adjusted by suitable nuts as shown.

The severing means 100 comprises three separate lower fixed knife edges and three corresponding upper, movable separate knives 103. The upper knives 103 are mounted on the yoke 104, mounted in the opposite guide blocks 105, fixed to the front and rear frames 18, 17.

The yoke 104 is pivotally mounted by the studs 106, or the links 107, suspended on the studs 108, carried by the oscillating levers 109, 110, respectively pinned to the shaft 111, mounted at its ends with suitable bearings carried by the rear and front

frames 17, 18. The lever 110 is provided with the stud 112, to which is pivoted the operating fork 113.

Means are provided for positive cutting actuation of the knives 100, 103 and for positively opening the severing means, and in the embodiment shown, the fork 113 is provided with the stud 114, on which is loosely mounted the upper roller 115, riding the external cam 116. The fork 113 is further provided with the lower stud 117, on which is loosely mounted the lower roller 118, cooperating with the cam 119.

The operating surfaces of the cams 116 and 119 are mounted on the power shaft 94. The fork 113 is guided by the block 120, loosely mounted on the shaft 94, whereby the wear is distributed over a relatively large surface contact, and in the event of undue wear, renewal of the block 120 alone is required.

The strip of paper board and finish paper, after being severed to the desired length or lengths by the aforesaid severing means 100, 103, and now designated 121, is passed onto the table 121^a, between the opposite side guides 122 and the upper guide 123. The side guides 122 are preferably beveled inwardly as indicated in plan view in Fig. 2, and are respectively of similar construction 95 of inward bevel as the side guides 70, as shown in Fig. 8.

The upper guide 123 is mounted on the block 124, clamped on the shaft 125, carried by and between the rear and front frames 17, 18. Such forward feeding of the severed strip 121 is effected by the rollers 126, 127, respectively driven by the intermeshing gears 128, 129.

Upper feed roller 127 and its gear 129 are loosely mounted on the stud 130, carried by the lever 131, supported on the shaft 132 and is arranged for positive lifting action manually, similar to the aforesaid sets of drop rollers 32, 43 and 68, 69. The upper roller shaft 132 is operated by the lever 133, provided with the stud 134, on which is pivotally mounted the fork 135, having the stud 136, in which is loosely mounted the roller 137 (see Figs. 1, 2, 4 and 14) cooperating with the cam 138, mounted on the power shaft 94. The roller 137 is held in coacting relation to cam 138 by the spring 139, having its one end attached to the lever 140, fixed to the upper roller shaft 132, and its other end attached to the rear frame 17. The lower roller shaft 141 is positively driven by the sprocket 142, meshing with the chain 143, driven by the sprocket 144, fixed on the shaft 145, journaled through the front frame 18, to which is fixed the pinion 146, meshing with the drive gear 147, fixed on the power shaft 94.

The fork 135, at proper timing of its cam 138, raises the upper drop roller 127, to re-

ceive the strip of paper board and finish paper 59 before being severed; immediately after the strip has been severed, the spring 139 draws down, under control of the cam 138 and fork 135, the upper drop roller 127 to engage the severed strip of paper board and finish paper 121. Upon closing of the upper drop roller 127, in operative relation to the lower roller 126, the gear 129 of the 10 upper roller 127 is brought into mesh with the gear 128 of the lower roller 126, whereupon the upper roller 127 is positively rotated synchronously with the lower roller 126 and feeds the severed strip 121 forwardly onto the table 121^a. Upon continued rotation of the power shaft 94, after the strip of paper board and finish paper has been severed, the holding clamp 99 remains in its clamped position and the toe 72 of the 15 feeding clamping means 72, 73, is first oscillated upwardly until the lugs 82, 83 engage one another on their respective rearward faces, and the spring 78 relieved of compression, whereafter the carriage 81 and 20 the feeding clamping means 72, 73 are returned to their initial positions, shown in full lines in Figs. 1, 2, 9 and 10.

It will be noted that the above described severing means provides for severing the 30 respective strips to form butt-joints.

Means are also provided for severing any strip to provide for lap joints, as for example, a joint formed of oppositely skived joining faces. Such lap joints may be provided for the tray rim and cover rim, but under prevailing practice the neck is of a 35 butt joint, irrespective whether the tray rim and cover rim are of skived or butt joints.

The skiving severing means is mounted in 40 the machine shown in the drawings, and arranged to be placed in operative relation and the upper knives 103 of the tray rim and cover rim severing means arranged to be removed.

45 The skiving severing means are particularly shown in Figs. 13 and 14. The two inclined skiving rotating, circular knife edges 150 cooperate with the aforesaid fixed lower knife edges 100, of the tray rim and cover rim mechanisms. Each skiving knife 150 is fixed on its operating shaft 151, loosely mounted in its supporting hub 152, carried by the carriage 153, slidably mounted on the guiding rails 154, mounted on the 50 opposite brackets 155, bolted to the rear and front frames 17, 18. Each shaft 151 is provided with the spiral gear 156, fixed thereto, driven by the spiral gear 157, provided with a key received in a rectangular longitudinal 55 key-way on the face of the shaft 145, driven as aforesaid by power shaft 94 through the gears 147, 146, see Fig. 4.

The carriage 153 is reciprocated by its link 158, pivotally connected with the arm 60 65 159, fixedly mounted on the shaft 160, jour-

naled in brackets 161, carried by the front frame 18. The shaft 160 is oscillated by its lever 162, provided at its free end with the loosely mounted roller 163, coacting with the cam 164, fixed on the power shaft 94, 70 see Figs. 13, 14 and 4.

The power shaft 94 is suitably driven by the fixed and loose pulleys 165, 166.

The cams 116, 119, 138 and 164 are preferably adjustably mounted on the power 75 shaft 94, as by providing the hub 167 of each cam with a circular perforation 168, intersecting to the desired extent the opening 169, receiving the power shaft 94. Within the perforation 168 is received the oppositely 80 disposed bushings 170, 171, closely fitted therein, and through the bushings extends the bolt 172 adjustable by means of its nut 173. The bushings 170, 171, are provided with inclined circularly cut clamping faces 85 174, 175, adapted to engage the shaft 94. The skiving knives 150, 150 are rendered inoperative when the machine is operated for butt joints, by disengaging the link 158 from its operating arm 159, by removing their connecting stud, and the carriage 153 locked on either rail 154 by means of a lock nut 148, see Fig. 13.

In the modified form of feeding and severing mechanism shown in Fig. 15, the feed 95 of the paper board and finish paper 59 is continuous, under control of the upper feed roller 176 and lower feed roller 177. The severing is performed by the upper cutting cylinder 178, provided with the knife edge 179, projecting from the cylinder face of the cutting cylinder 178, cooperating with the lower cylinder 180, preferably of hard and ground steel, said cylinders 178, 180 being mounted to provide a minute clearance between the cutting edge 179 and the surface of the lower cylinder 180, when in cutting position. The severed strip of paper board and finish paper 121 is fed forward by the feed rollers 181, 182, onto the table 121^a, 100 aforesaid. Such form of continuous feed and cutting mechanism replaces the aforesaid reciprocating feed 72, 73 and carriage 81 and the aforesaid butt severing means 105 100, 103, and the aforesaid skiving means 110 150. The shaft 111 and its aforesaid operated parts are removed, and the control fork 135 removed, whereby the rollers 127, 128 become continuously operating feed 115 rollers. 120

Upper cutting cylinders 178, of different diameters are employed for obtaining different severed lengths. The severed strips of paper board and finish paper are cut to the desired lengths respectively for the tray 125 rim, neck and cover rim, such lengths being generally adjusted by the stud 90 in the slotted arm 88 and specifically for the respective strips by the stud 87 in the slotted end of the lever 87. 130

The respective parts of the continuous feed and cutting mechanism are mounted on the indicated shafts journalled in the rear and front frames 17, 18. The anterior feed rollers 176, 177 are intergeared, similarly the cutting cylinders 178, 180 and similarly the position feed rollers 181, 182. The shafts of the lower feed rollers 177, 182 and the lower cutting cylinder 180 are directly driven by gearing connecting with the power shaft 94, as will be understood. Preferably the adhesive fountain 28 provides adhesive in common to the three applying rolls 29, whereby substantially the same, or uniform consistency of adhesive is supplied to the respective tray rim, neck and cover rim parts of the respective boxes, as formed, in accordance with the principle above stated, of forming the parts of any box at substantially the same time, i. e., preferably respectively under the same temperature and humidity conditions. Such plurality of rolls in the common fountain serve also to agitate the adhesive and maintain the consistency.

It will be noted that the respective strips of paper board and the strips of finish paper for the cover, neck and tray rim of each box are treated and progressed through the machine at substantially the same time and under the same temperature and humidity conditions, together with the application of adhesive, whereby the paper board and finish paper are subjected to substantially the same conditions.

It will be apparent that the machine is applicable, also for the treatment of a single strip of paper board and of finish paper for any given part of any box, and similarly for two or other number of parts of any box, by utilizing a corresponding part or parts of the machine described above.

Whereas, we have described our invention by reference to specific forms thereof, it will be understood that many changes and modifications may be made without departing from the invention as defined by the appended claims.

We claim:

1. A paper box making machine comprising means for mounting paper board respectively for the cover, neck and tray of the box, means for respectively mounting finish paper for the respective paper board, for the cover, neck and tray of the box, and means for applying the finish paper to the respective strips of paper board, said means comprising a plurality of pressure applying rolls adapted to individually apply the three strips of finish paper to the respective three

strips of finish board and common means for raising said individual rolls.

2. A paper box making machine comprising means for mounting paper board respectively for the cover, neck and tray of the box, means for respectively mounting the finish paper for the respective paper board, for the cover, neck and tray of the box, and means for applying the finish paper to the respective strips of paper board, said means comprising a plurality of pressure applying rolls, means for individually mounting said pressure applying rolls, and common means for raising said individual rolls.

3. A paper box making machine comprising means for applying a strip of finish paper to a strip of paper board, means for advancing the resulting applied finish paper and paper board and severing means, said severing means comprising means for severing the strip for a butt joint, means for severing the strip for a skived joint and a common means for selectively actuating said butt severing means or said skived severing means.

4. In a paper box making machine, supporting means, individual means for respectively feeding a plurality of strips of paper on said supporting means, common means for holding said plurality of strips of paper under pressure on said supporting means, means operative upon operation of said common holding means for rendering said feeding means non-operative, commonly operative means for severing said plurality of strips, means operative in advance of and during the operation of said severing means for operating said pressure holding means and common means for releasing said pressure holding means.

5. In a paper box making machine, supporting means for receiving a plurality of paper strips, means for individually feeding said plurality of paper strips, on said supporting means, individual severing means for severing said plurality of paper strips, common means for operating said severing means, holding means for said plurality of paper strips, mechanism for operating in common said holding means in advance of and during the stage of operation of said severing means, and means operative upon operation of said severing means for rendering said feeding means non-operative.

In testimony whereof, we have signed this specification this 15th day of February, 1919

ALLAN A. ADAMSON.
WILLIAM F. GRUPE.
